UNITED STATES PATENT OFFICE.

BYRON WILLETT, OF PLYMOUTH, MICHIGAN.

AIR-GUN.

1,113,077.

Specification of Letters Patent.

Patented Oct. 6, 1914.

Application filed April 1, 1914. Serial No. 828,672.

To all whom it may concern:

Be it known that I, BYRON WILLETT, a citizen of the United States of America, residing at Plymouth, in the county of Wayne 5 and State of Michigan, have invented certain new and useful Improvements in Air-Guns, of which the following is a specification, reference being had therein to the accompanying drawings.

10 This invention relates to air guns of that type wherein spring actuated plungers are set or cocked and then released to eject or discharge shots or other projectiles, and my invention aims to provide: First, a repeater 15 or magazine air gun having the action of an ordinary fire arm and possessing other prerequisites that insure safety and rapid and easy manipulation. Second, a fire arm that is strictly a boy's gun in every detail; the 20 construction and arrangement of parts being such that the gun can be taken apart and easily and safely assembled without the use of special tools, thus allowing a boy to satisfy his curiosity as to the mechanical construction and action of the gun, all of which is accomplished by removing a single screw or pin. Third, a gun of the above type embodying a novel projectile starting rod or 25 plunger that affords a non-frictional two point bearing for a spring, the construction 30 and the design of the plunger being such that it can be easily placed in the gun and engaged by a trigger to hold the plunger in a retracted position and the spring thereof 35 under tension or compression. Fourth, a gun of the above type embodying telescopic barrel and stock frames that are stamped and pressed from sheet metal and permit of easy access being had to a reciprocal trigger supporting member and other parts of 40 the gun.

My invention further aims to accomplish the above and other objects by a simple, durable and inexpensive mechanical construction that will be hereinafter specifically described and then claimed, and reference will now be had to the drawings, wherein—

Figure 1 is a longitudinal sectional view of a portion of the gun; Fig. 2 is a longitudinal sectional view of the outer end of the barrel of the gun; Fig. 3 is an end view of the same; Fig. 4 is a cross sectional view taken on the line IV—IV of Fig. 1; Fig. 5 is a cross sectional view taken on the line 55 V—V of Fig. 1; Fig. 6 is a similar view taken on the line VI—VI of Fig. 1; Fig. 7

is a similar view taken on the line VII—VII of Fig. 1; Fig. 8 is a longitudinal sectional view of the barrel or outer frame; Fig. 9 is a similar view of the stock or inner frame; Fig. 10 is a longitudinal sectional view of a portion of the gun showing the same uncocked; Fig. 11 is a similar view showing the barrel frame and stock frame partly separated, illustrating the manner of withdraw- 60 ing the plunger from the barrel of the gun; Fig. 12 is a longitudinal sectional view of a portion of the gun barrel, illustrating a forward sight; Fig. 13 is an end view of the same; Fig. 14 is a perspective view of a detached trigger rod; Fig. 15 is a perspective view of a detached forward sight, and Fig. 16 is a cross sectional view of a rear sight, showing the manner of holding the same.

In describing my invention by aid of the 75 drawings above referred to, I desire to point out that I intend the views as merely illustrative of an example whereby my invention may be applied in practice, and I do not limit the same to the precise arrangement and construction of parts shown. The following description is therefore to be broadly construed as including substitute arrangements and constructions which are the 80 obvious equivalent of those shown.

In the drawings 1 denotes a gun barrel having the inner end thereof provided with an integral frame comprising depending parallel side walls 2 that are disposed at a tangent relatively to the periphery of the 90 barrel and have the longitudinal edges thereof inclined. The outer ends of the walls 2 are contracted and terminate in apertured lugs 3, said lugs being located at the outer end of the oblong opening 4 formed in the 95 bottom of the barrel in conjunction with the frame thereof. The inclined edges of the walls 2, adjacent the inner ends thereof, are provided with inwardly extending up-turned lips 5 to receive the depending parallel walls 100 6 of a stock frame 7 shaped and designed to slide into the barrel frame. The upper part of the stock frame is cylindrical and together with the walls 6 is adapted to snugly engage the inner walls of the barrel frame, 105 as best shown in Fig. 7. The outer end of the stock frame is closed, as at 8, with the exception of a slot 9 and this end of the stock frame constitutes a rear abutment, for a purpose that will presently appear. The 110 same end of the stock frame has the walls 6 thereof contracted to provide apertured lugs

10 adapted to register with the apertured lugs 3 of the barrel frame. The inner end of the stock frame terminates in large apertured ears 11 and it is between these ears that a 5 gun stock 12 is secured by transverse fastening means 13, also by a screw 14 or other fastening means extending through the top of the stock frame and into the top of the stock, as best shown in Fig. 1.

10 Slidably mounted in the stock frame 7 is a tubular reciprocal trigger supporting member 15 having the bottom side thereof provided with an integral oblong casing 16 that extends between the walls 6 of the stock 15 frame 7. The bottom of the casing 16 has a slot 17 providing clearance for the finger piece 18 of a trigger 19 pivotally mounted in the member 15 by a transverse pin 20. The catch member 21 of the trigger is beveled 20 and engaged by a flat spring 22 arranged within the casing 16 and held in position by a transverse pivot pin 23 that has the ends thereof protruding from the sides of the casing 16 to serve as pivots for a channel link 24, which has the outer end thereof pivotally connected by a pin or rivet 25 to an apertured lug 26 carried by a break down lever 27. The lever 27 is of the ordinary and well known type having a trigger guard 28 30 and a handle 29, and the outer end of said lever is pivotally and detachably mounted between the apertured lugs 10 by a screw bolt 30 and a nut 31. As a matter of good construction, the nut 31 is soldered or otherwise secured to the outer side of one of the apertured lugs 3 of the barrel frame and the head of the screw bolt 30 is made whereby it can be easily rotated by a screw driver or a coin inserted in the slot of the head, and 40 it is in this connection, that this single screw bolt maintains the principal parts of the gun together by passing through the lugs 3 and 10 and locking the stock frame within the barrel frame. See Fig. 4.

45 Intermediate the ends of the barrel 1 is a forward abutment 32 in the form of a collar that is suitably mounted within the barrel. The collar has the opening thereof flared or beveled in two directions and the opening of said collar receives a tubular projectile starting rod 33. The bore of the tubular rod has the outer end thereof flared to provide a seat 34 for a shot or projectile and the inner end of the rod is soldered or otherwise connected to a metallic disk 35 carried by a cross head 36 of a trigger rod 37. The trigger rod 37 is in the form of a flat bar that extends through the slot 9 of the rear abutment, said trigger rod having the inner end thereof twisted and provided with a longitudinal slot 38 to receive the catch member 21 of the trigger 19. The twisted portion of the trigger rod retains the same in engagement with the inner or stock frame, when the stock frame is removed, either with the trigger in

engagement with the rod or out of engagement, but permits of the rod and stock frame being easily separated after the stock frame is removed from the cutter or barrel frame. The trigger rod affords a two point bearing 70 for a coiled spring 39 encircling said rod between the cross head 36 and the rear abutment, said spring constituting means for ejecting or discharging shot or similar projectiles from the gun. 75

The cross head 36 is provided with outwardly extending pins or rivets 40 and arranged upon said pins and encircling the rod 33 is a packing ring 41 and a retaining ring or washer 42, said ring and said washer being retained in position by the pins or rivets 40. The tubular starting rod 33, contiguous to the washer 42, has an air outlet port 43 which permits of the plunger moving forward in the inner end of the outer barrel. 85

Arranged longitudinally of the barrel 1 and extending from the outer end thereof to the forward abutment 32 is an inner concentric barrel 44 and the space between the inner and outer barrel constitutes a magazine or receptacle for shot or other projectiles. The inner end of the barrel 44 is tapered to fit in the opening of the forward abutment and mounted upon the inner end of said barrel are spaced disks 45 and 46, the latter being disposed at an angle or incline relatively to the barrels 44 and 1 and said disks are connected by a longitudinal casing or tube 47. The outer end of the casing 47 communicates with an opening 48 in the 100 disks 46 and said casing also communicates with the inner barrel 44 by an opening 49. The openings 48 and 49 are of a sufficient size to permit of a shot or projectile passing from the magazine of the barrel into the 105 casing 47 and then into the inner barrel 44 to be impinged by the starting rod 33 of the plunger.

Soldered or otherwise mounted upon the outer end of the inner barrel 44 is a cap 50 110 having the periphery thereof knurled to facilitate rotating the same. The inner side of the cap 50 has a concentric collar 51 adapted to fit in the end of the outer barrel 1. The collar 51 has a cam slot 52 and a depressed portion 54 in communication therewith, said depressed portion providing clearance for an inwardly projecting lug 53, carried by the outer barrel 1. The lug 53 is adapted to engage the walls of the cam slot 115 52 and draw the collar 51 into the outer barrel as the cap is rotated clockwise. A counter-clockwise movement of the cap places the depressed portion 54 in alignment with the lug 53, whereby the collar can be withdrawn 120 from the outer barrel. The outer end of the barrel 1 has an off-set portion or recess 55 to receive the base 56 of a forward sight 57. The sight, *per se*, may be of a conventional form, and the base 56 has a depending lug 130

58 that is engaged by the collar 51 to retain the forward sight in engagement with the barrel. A rear sight 59 is held between the barrel and stock frames and alines with the 5 forward sight.

The spring pressed trigger 19 can readily ride into engagement with the inner end of the trigger rod 37 whereby the catch 21 enters the slot 38 of said rod, when the break 10 down lever 27 is shifted to recock the gun. As illustrated in Fig. 10, the break down lever is in an open position ready to be closed to place the spring 39 under compression, the cocked position of the gun being 15 shown in Fig. 1. When the trigger is pulled the trigger rod 37 is released and the projectile starting rod 33 ejects the single shot or projectile from the inner barrel 44. The recocking of the gun can be easily performed 20 without removing the gun from the shoulder, as the break down lever can be easily manipulated with one hand while the other hand retains the gun in engagement with the shoulder.

25 I attach considerable importance to the manner in which the barrel and stock frames are assembled and to the fact that the screw bolt 30 or its mechanical equivalent is the only element necessary to lock one frame 30 within the other. Furthermore, that by removing the stock frame, easy access is had to the plunger of the gun and that while the stock frame is detached the reciprocal trigger supporting member cannot become accidentally displaced. This member is easily 35 shifted in the stock frame by the break down lever and the connections with said lever are such that the closing movement of said lever is limited and said lever retained in a closed 40 position by the tension of the spring 39 and also by reason of the connection between said lever and the link 24 being to one side of an imaginary line connecting the pin 23 and the screw bolt 30. This is apparent by reference 45 to Fig. 1 showing the gun cocked.

It is possible to make the outer barrel 1 of a length to accommodate one, three or five hundred shots and irrespective of the capacity of the magazine, it is only possible for 50 one shot to enter the inner barrel at a time. The shots are easily placed in the magazine by raising the cap 50 and the casing 47 places the shot in position to enter the inner barrel 44.

55 What I claim is:

1. In a gun, a stock frame, a barrel frame telescoping said stock frame, a reciprocal trigger supporting member slidable in said stock frame, a break down lever adapted to 60 move said member, and means for simultaneously connecting said frames and said lever.

2. In an air gun, a stock frame, a barrel frame telescoping said stock frame, a trigger member movable in said stock frame, a 65

plunger adapted to be retracted by said trigger member, means for moving said trigger member, and detachable means connecting said frames and supporting the first mentioned means.

3. In an air gun, telescopic frames, a trigger member reciprocal in one of said frames, a plunger extending into the same frame and adapted to be engaged by said trigger member, a break down lever for moving said 70 trigger member, and means connecting said frames and adapted to support said break down lever.

4. In an air gun, a barrel, telescopic frames at the inner end of said barrel, a plunger movable in said barrel and extending into one of said frames, a trigger member reciprocal in the same frame and adapted to engage said plunger, a break 75 down lever adapted to shift said trigger member, and means connecting said frames and supporting said break down lever.

5. In an air gun, inner and outer barrels providing a projectile magazine, inner and outer frames at the inner end of said outer 90 barrel, a stock carried by said inner frame, a spring actuated plunger arranged in said outer barrel and protruding into said inner barrel and into said inner frame, a trigger supporting member reciprocal in said inner 95 frame and adapted to engage said plunger, a break down lever adapted to shift said member, and means detachably connecting said frames and supporting said lever.

6. In an air gun having a rigidly held 100 stock in contra-distinction to those having break-down stocks or barrels, a barrel, rigidly connected inner and outer frames supported thereby, said inner frame providing a stationary rear abutment, a plunger within 105 said barrel and extending through the rear abutment of said inner frame, cocking means within said inner frame for holding said plunger in a retracted position, and means supported by the connection between said 110 frames for actuating said cocking means.

7. In a gun, a barrel, inner and outer frames carried thereby, a spring actuated plunger movable in said barrel, a trigger member reciprocal in said inner frame and 115 adapted to hold said plunger in a retracted position, a lever carried by said inner and outer frames for shifting said trigger member, and a link connection between said trigger member and said lever adapted to be 120 housed by said frames.

8. In a gun, a barrel, a stock frame supported in the inner end thereof and providing a rear abutment, a spring actuated plunger movable in the rear abutment of 125 said stock frame and extending into said barrel, a trigger member in said stock frame adapted to be connected to said plunger, and a lever supported at the outer end of said stock frame and having connection with said 130

trigger member for moving said member and said plunger.

9. In a gun, a barrel, a stock frame supported in the inner end thereof and providing a rear abutment, a front abutment in said barrel, a spring actuated plunger movable in said abutments, a trigger member movable in said stock frame adapted to be connected to said plunger, a break down lever supported at the outer end of said stock

frame, and a link connection between said trigger member and said lever and adapted to be housed by said stock frame.

In testimony whereof I affix my signature in presence of two witnesses.

BYRON WILLETT.
